UNITED STATES PATENT OFFICE.

WILLIAM FRANKLIN ALLEN, OF NASHVILLE, TENNESSEE.

DESIGN FOR A STOVE.

Application filed January 6, 1926. Serial No. 15,970. Term of patent 7 years.

To all whom it may concern:

Be it known that I, WILLIAM FRANKLIN ALLEN, a citizen of the United States of America, and a resident of Nashville, in the county of Davidson and State of Tennessee, have invented a new, original, and ornamental Design for Stove, of which the following is a specification.

Reference is to be had to the accompanying drawing in which the figure is a perspective view of a stove showing my new design.

I claim—

The ornamental design for a stove as shown.

WILLIAM FRANKLIN ALLEN.
